UNITED STATES PATENT OFFICE.

RAY V. GRIGGS, OF CHICAGO, ILLINOIS.

DESIGN FOR A TELEPHONE-SUPPORTING BRACKET.

SPECIFICATION forming part of Design No. 34,482, dated May 7, 1901.

Application filed March 25, 1901. Serial No. 52,874. Term of patent 7 years.

To all whom it may concern:

Be it known that I, RAY V. GRIGGS, a citizen of the United States, residing at Chicago, in the county of Cook and State of Illinois, have invented and produced a certain new and original Design for a Telephone-Supporting Bracket, (Case No. 2,) of which the following is a full, clear, concise, and exact description, reference being had to the accompanying drawings, forming a part of this specification.

My invention relates to brackets for supporting telephone-desk sets and will be described in connection with the accompanying drawings, in which—

Figure 1 is a side elevation of the bracket; Fig. 2, a plan view thereof, and Fig. 3 a bottom view thereof.

Like parts are indicated by similar characters of reference in the different figures.

The anchoring-arm *a* is in the form of a flat bar provided with holes *b b* and terminating in a cylindrical socket *c*, whose top is below the top edge of the anchoring-arm and which extends below the bottom edge of the anchoring-arm. The bracket has its arm *d* terminating at one end in the form of a **U**,

the sides *e e* of which embrace the cylindrical portion *c*. A pintle *f* projects through the sides *e e* and the cylindrical portion *c*. The 30 pintle is provided with a tapered lower terminal *g* and a rounded upper terminal *h*, beads *i* and *k* intervening between the rounded and tapered ends and the remainder of the pintle. The bracket-arm *d* has a right-angular extension *l*, rectangular in cross-section, as illustrated in Fig. 3. This extension *l* supports a circular pan *m* for supporting the telephone set. A V-shaped notch *n* is provided in the rim of the pan. The arm *l* supports the pan 40 at the center thereof.

Having thus described my invention, what I claim as new, and desire to secure by Letters Patent, is—

The design for a telephone - supporting 45 bracket, substantially as herein shown and described.

In witness whereof I hereunto subscribe my name this 22d day of March, A. D. 1901.

RAY V. GRIGGS.
